UNITED STATES PATENT OFFICE.

GUY C. HEILMAN, OF HACKENSACK, NEW JERSEY, ASSIGNOR OF ONE-HALF TO MARY A. HERRICK, OF NEW YORK, N. Y.

GAS-PRODUCER.

No. 866,181.

Specification of Letters Patent.

Patented Sept. 17, 1907.

Application filed March 4, 1907. Serial No. 360,331.

To all whom it may concern:

Be it known that I, GUY C. HEILMAN, a citizen of the United States, residing in the city of Hackensack, in the county of Bergen and State of New Jersey, have **5** invented certain Improvements in Gas-Producers, of which the following is a specification:

This invention is a gas producer comprising a hopper containing a screw for effecting a regulated feed, a breaker for reducing the size of the fuel, and a spout **10** for distributing the broken fuel within the producer body, the screw, breaker and spout being fixed to and revolved by a journaled shaft.

In the drawings, Figure 1 represents a sectional elevation of my invention; Fig. 2 represents a top plan **15** view of the hopper, and Fig. 3 represents a plan view of the detached spout.

In the drawings is shown the top of a producer body **20** 1 having a cover 2 containing an aperture 3. Surrounding the aperture and fixed to the cover is a ring 4 which supports a hopper comprising the oppositely tapering conical sections 5 and 6 having a throat 7, an inlet 8 being formed in the closed top 9. A spout 10, having a cylindrical body portion 11 disposed within the aperture 3 and the ring 4, is provided **25** with a circular flange 12 revolvably mounted within the bearing 13 of the ring 4, the outlet from the spout being disposed eccentrically and angularly to its axis of revolution. A spider 14 is fixed within the body of the spout and has fixed thereto a shaft 15 journaled in **30** the bearing 16 of the hopper cover 9. This shaft, driven by a worm wheel 17 thereon and the worm 18 engaging the worm wheel, has fixed thereto a conical screw propeller 19 within the conical section 5 and a conical breaker or grinder 20 within the conical section **35** 6. The breaker is provided with the projections 21

forming a roughened surface and the section 6 is provided with the projections 22 forming a roughened surface coating with the surface of the part 20.

It will be understood that in operation fuel fed through the opening 8 in the hopper cover 9 into the **40** hopper section 5 is propelled by the tapered screw 19 at a uniform rate through the throat 7 into the tapered section 6. Here it is crushed by the grinder 20, and delivered therefrom by the revolving spout 10 within the body of the producer, being distributed circularly **45** and in a uniform manner over the fuel in the body of the producer.

Having described my invention, I claim:

1. In a gas producer, a body having a cover, a hopper fixed to said cover, a propelling device and a grinding device revolvable within said hopper, and a revolvable spout **50** for distributing fuel within said body.

2. In a gas producer, a feed hopper having oppositely disposed conical sections, a spout to which said hopper delivers, and a journaled shaft having a screw propeller **55** 55 thereon within one of said conical sections, said spout being fixed to and revolved by said shaft.

3. In a gas producer, a feed hopper having oppositely disposed conical sections diverging from each other, a spout to which said hopper delivers, and a journaled shaft **60** 60 having a grinder thereon within one of said conical sections, said spout being fixed to and revolved by said shaft.

4. In a gas producer, a hopper having oppositely disposed conical sections, a revolvable shaft having fixed thereon a screw propeller within one of said conical sections and a grinder within the other of said sections, and a spout fixed to and revolved by said shaft to which said **65** hopper delivers.

In testimony whereof, I have hereunto set my name this **70** 20th day of February, 1907, in the presence of the subscribing witnesses.

GUY C. HEILMAN.

Witnesses:

I. M. TITUS.

JAMES E. CLARK.
